UNITED STATES PATENT OFFICE.

RUDOLPH C. MILLER, OF RENO, NEVADA.

FUSE-CAP PROTECTOR.

1,081,854.

Specification of Letters Patent. Patented Dec. 16, 1913.

Application filed August 11, 1913. Serial No. 784,243.

To all whom it may concern:

Be it known that I, RUDOLPH C. MILLER, a citizen of the United States, residing at Reno, in the county of Washoe and State of Nevada, have invented a new and useful 5 Fuse-Cap Protector, of which the following is a specification.

The present invention appertains generally to fuse caps and relates particularly to 10 a protector for fuse caps.

It is the object of the present invention to provide a novel and improved device, of simple and inexpensive construction, which may be conveniently and efficiently applied 15 over a fuse cap, to render the fuse cap waterproof and to tightly secure the fuse cap over the fuse.

The invention has been illustrated in its preferred embodiment in the accompanying 20 drawing, wherein:

Figure 1 is an elevation of the end of a fuse and fuse cap, with the improved protector applied thereto. Fig. 2 is a longitudinal section thereof, the fuse being shown 25 in full. Fig. 3 is a perspective view of the protector prior to application to the fuse cap.

The present device is of such a nature, as 30 to be applicable to any suitable blasting fuse 1, over the end of which the fuse cap 2 is slipped, fuse powder 3 being held within the head of the cap and being brought against the end of the fuse when the cap is slipped 35 over the fuse. The fuse cap 2 is usually of copper, brass, or a suitable alloy.

In carrying out the present invention, there is provided a sleeve or band 4 of lead 40 or other soft metal, and of an internal diameter slightly larger than the external diameter of the cap 2. It will be apparent that the sleeve or band 4 may be of any suitable size, according to the dimensions of 45 the fuse cap with which the protector is employed.

After the fuse cap has been engaged over the end of the fuse, the sleeve or band 4 is slipped over the fuse cap, so that its intermediate portion stands over the rim or mouth of the fuse cap, in which event, the 50 sleeve or band is compressed by means of a pair of pinchers, pliers, or any other suitable implement, so that the sleeve or band very tightly embraces the open end portion or mouth of the cap and the adjoining exposed portion of the fuse. The sleeve or

band in being contracted, will compress the mouth or open end portion of the fuse cap, in order that the crimped or contracted portion of the fuse cap, will tightly grip and compress the fuse to lock the fuse cap on 60 the fuse. The ends of the sleeve or band may also be battered or worked against the fuse cap and fuse, to assist in locking the fuse cap upon the end of the fuse. When the sleeve or band has thus been applied to 65 the fuse and its cap, there will be no liability of water, moisture, or other extraneous matter entering the fuse cap, which would be objectionable. Thus, the present device serves the double function of rendering the 70 fuse cap water proof, and of locking the fuse cap over the end of the fuse.

The present device is extremely simple and inexpensive, and is readily and efficiently applicable over a fuse cap, and, when 75 applied, will not encumber the fuse cap to any appreciable extent. The sleeve or band will also protect the fuse while a blast hole is being loaded or packed, and while the powder is being tamped, it being noted that 80 should the fuse cap be forced against a rock, or other hard substance, there will be no tendency to release the protector, or to injure it in any manner. The present device does not require any preliminary crimping 85 of the fuse cap, and otherwise eliminates any encumbering or expensive elements.

What is claimed is:—

1. In combination, a blast fuse, a fuse cap inserted over the end thereof, and a soft 90 metallic band slipped over the mouth of the fuse cap and compressed to compress the mouth of the cap and the adjoining portions of the fuse.

2. In combination, a blasting fuse, a fuse cap inserted over the end thereof, and a soft 95 metallic sleeve inserted over the cap with its intermediate portion disposed over the mouth of the cap, and the sleeve being compressed over the mouth of the fuse cap and 100 over the adjoining portions of the fuse, to compress the mouth of the cap and the said portions of the fuse.

In testimony that I claim the foregoing as my own, I have hereto affixed my signature in the presence of two witnesses.

RUDOLPH C. MILLER.
